(57) **CLAIM**

The ornamental design for a faucet, as shown and described.

DESCRIPTION

FIG. 1 is a front and right perspective view of a faucet showing our new design;

FIG. 2 is a front view thereof;

FIG. 3 is a rear view thereof;

FIG. 4 is a top view thereof;

FIG. 5 is a left side view thereof; and,

FIG. 6 is a right side view thereof.

A bottom view is omitted since the bottom view is invisible in normal use.

The broken lines depict portions of the Faucet in which the design is embodied that form no part of the claimed design.
